UNITED STATES PATENT OFFICE.

JOE STASYSZEN, ELIZABETH STASYSZEN, AND EMILIA STASYSZEN, OF BREMOND,
TEXAS.

COMBINATION COMB AND BRUSH.

Application filed February 7, 1922. Serial No. 534,681.

To all whom it may concern:

Be it known that we, JOE STASYSZEN, ELIZABETH STASYSZEN, and EMILIA STASYSZEN, citizens of the United States, residing 5 at Bremond, in the county of Robertson and State of Texas, have invented certain new and useful Improvements in Combination Combs and Brushes, of which the following is a specification.

10 One of the objects of this invention is to provide a toilet article comprising a hair brush having means by which a comb may be brought into a position adapted to practical use.

15 Another object is the means provided for folding the comb into a recess formed in the back of the brush.

20 A further object is the means provided by which the comb may be rotated in and out of operative position when the locking catch is released.

25 These and other objects are attained by the novel construction and combination of parts hereinafter described and shown in the accompanying drawing, forming a material part of this disclosure and in which:—

Figure 1 is a plan view of the brush with the comb in inoperative or folded position.

30 Figure 2 is a side elevation of the same. Figure 3 is a partial sectional view showing the comb raised and the latch withdrawn.

35 Figure 4 is a transverse sectional view showing the comb operating mechanism, taken on line 4—4 of Figure 1.

Figure 5 is a perspective view showing the latch element in detail.

40 Referring to the drawing in detail, the numeral 5 designates in general the back of a hair brush having a handle 6, in the top of which is a recess 7 adapted to receive a comb 8.

45 A cylindrical rib or backing 9 is formed integral with the comb, and pintles 10 are provided concentric with the ends of the rib 9, forming bearings passing thru openings in the angle plates 11 and 12, fixed at opposite ends of the recess 7, and held by the screws 13, engaging the brush back.

50 One of the pintles 10 extends through the angle plate 12 and is provided with a squared section 14, adapted to enter a rectangular recess 15 formed in the end of a

latch 16, provided at the opposite end with an upright projection or finger piece 17 for 55 sliding the latch.

This latch operates in a recessed groove and is held by a plate 18 set flush with the brush back and has a slot 19 for limiting the movement of the latch. A spring 25 provides friction for holding the latch in or 60 out of engagement with the comb.

Formed about the periphery of the comb rib 9 and midway of its length, are gear teeth 20, meshing with the teeth of a rack 65 21, sliding transversely in a slot formed in the back of the brush body, and provided with a slot 22 in which is a holding screw 23 for limiting the travel of the rack. A projecting upturned end 24 provides a finger 70 hold for operating the rack.

Bristles 26 are fixed in a plate 27 in the usual manner and may be removably secured to the brush back 5.

The comb is held in either its retracted 75 or extended position due to the frictional effect of the rack 21, the latter being made of resilient material and close-fitted to avoid sliding except when considerable force be used.

80 As changes of construction could be made within the scope of the invention, it is intended that all matter contained in the foregoing description or shown in the accompanying drawing, shall be interpreted as illustrative and not in the limiting sense.

Having thus described my invention, what I claim as new and desire to secure by Letters' Patent, is:—

1. A toilet article comprising a comb, a 90 hair brush consisting of bristles secured to a backing body, depressions formed on one of the sides of said body receptive of the comb, means for rotatably engaging said comb with brackets fixed in the brush body, 95 gear teeth integral with the comb, a sliding rack meshing with the gear teeth, said rack being operably embedded in the brush body, means with said rack for causing partial rotation of said comb, and means for preventing said comb from being rotated.

2. A toilet article comprising a hair brush and a comb associated therewith, said comb having a longitudinal cylindrical rib, pintles 105 extending from the ends of said rib, one of said pintles having a terminating portion

rectangular in section, recessed depressions formed in the brush body adapted to receive the comb, a lock slidable in said brush body, a rectangular opening formed in the lock 5 adapted to engage the rectangular end of the comb pindle, means for rotating said comb through an arc of 90 degrees, and

means with said sliding lock for securing the comb in either horizontal or vertical position.

10

In witness whereof we affix our signatures.

JOE STASYSZEN.

ELIZABETH STASYSZEN.

EMILIA STASYSZEN.
